UNITED STATES PATENT OFFICE.

HARRY P. FAIRCHILD, OF NEW YORK, N. Y.

MAGAZINE-PENCIL.

1,345,436.

Specification of Letters Patent.

Patented July 6, 1920.

Application filed April 5, 1917. Serial No. 159,849.

To all whom it may concern:

Be it known that I, HARRY P. FAIRCHILD, a citizen of the United States, residing at New York, in the county and State of New 5 York, have invented certain new and useful Improvements in Magazine-Pencils, of which the following is a full, clear, and exact description.

This invention relates to lead pencils of 10 the so-called "magazine" type, preferably a pencil of the type that propels and also retracts (or "repels") the lead, and its chief object is to provide in the body of the pencil a convenient and simple magazine for 15 storing additional leads. Another object is to provide a pencil of the type indicated with a magazine which in no way complicates the lead-actuating mechanism, but cooperates therewith in such manner as to materially strengthen the same. A further 20 object is to provide a pencil of simple and reliable construction which can be manufactured at reasonable cost. To these and other ends the invention consists of the novel 25 features of construction and combinations of elements hereinafter described.

Of the various embodiments of which the invention is capable I have selected for illustration and specific description herein the 30 one that at the present time is believed to exhibit the invention in its most convenient and effective form. This embodiment is shown in the accompanying drawing, in which—

35 Figure 1 illustrates the outer appearance of the complete pencil.

Fig. 2 is a longitudinal section of the complete pencil, on a larger scale than that of Fig. 1.

40 Fig. 3 is a detail side view, on about the same scale as Fig. 2, of the helically slotted tube or cylinder used in the actuating mechanism.

Fig. 4 is a cross section on line 4—4 of 45 Fig. 2.

Fig. 5 is a detail side view of the magazine sleeve, showing the same attached to the helically slotted tube or cylinder of Fig. 3.

50 Fig. 6 is a detail perspective view of the rear end of the pencil, showing the lead magazine opened by removal of the knob.

The outer casing or barrel 10 may be made of gold, silver, or any other suitable metal 55 or material, and in its forward end is fitted a hollow tapered or conical tip 11, the two

being axially alined and so fitted that either can rotate with respect to the other.

The lead actuating mechanism is preferably, but not necessarily, of both the propelling and repelling type, and in the present embodiment of the invention comprises a tubular guide 12 extending longitudinally of the barrel and co-axial therewith, and provided with a longitudinal slot 13. In the 60 guide is a short tube 14 constituting the carrier for the lead 15, the latter being inserted in the forward end of the tube. At its rear end the carrier has a lug 16 extending radially through the guide slot 13. In 65 the tube is a plunger 17, conveniently formed of a piece of wire with its rear end bent up to form a lug 18, which, like the lug 16, extends radially through the guide slot 13. Evidently, if the carrier 14 and 70 plunger 17 are shifted in the guide 12 in unison, that is, both moving together, the lead will be advanced, or retracted, as the case may be; but if the plunger is shifted forwardly (toward the left in Fig. 2) in the 75 carrier it will push the lead out of the carrier, leaving the latter ready to receive a fresh piece of lead when the plunger is retracted. From this function of the plunger it may be conveniently termed an 80 "ejector," its purpose being to eject the small bit of lead that is left behind in the carrier when the lead is accidentally broken off. To actuate the carrier and ejector as described, a sleeve or tube 19 is provided, encircling 85 the guide tube 12 and fitting the same snugly, but permitting each to turn smoothly with respect to the other. The sleeve 19 has a helical slot 20, into which the lugs 16 and 18 project, the latter being spaced apart in successive turns of the helix, as clearly shown 90 in Fig. 3. The forward end of the guide 12 is fixed to the tip 11 in any convenient way, and the actuating tube or sleeve 19 is rigidly connected to the barrel 10, preferably in the 95 manner hereinafter described. It will therefore be clear that if the barrel is rotated relatively to the tip, thereby rotating the actuating tube or sleeve about the guide tube, the carrier 14 and ejector 17 will move together 100 lengthwise of the pencil and the lead will be advanced or retracted according to the direction of the rotation. For the purpose of advancing and retracting the ejector with respect to the carrier, the outermost 105 turn of the helical groove 20 is cut off flat or square, as shown at 21 in Fig. 3. Conse-

quently, when the actuating sleeve is rotated enough to bring the carrier-lug 16 to the "square" portion of the slot, say to the position indicated by the dotted line at 16^a, Fig. 3, further turning of the sleeve will not advance the carrier farther. On the other hand, the ejector lug 18 is still in the inclined or helical portion of the slot, as at 18^a, and hence will continue to move forward, thereby pushing the lead ahead of it and out of the carrier. Upon reversing the direction of rotation the ejector is of course retracted first, thus permitting a fresh lead to be inserted into the now open end of the carrier.

At the forward end the actuating sleeve 19 bears against the tip 11, and at its rear end it is held by a collar 22 encircling the end of the guide 12, the collar being held in place by a pin 23.

It will be observed that the propelling and repelling mechanism is considerably smaller in diameter than the barrel, thus leaving an annular space inside the latter. Advantage is taken of this space to provide a magazine or receptacle for spare leads, and the device which is employed for the purpose in the preferred form of the invention, in which the helically slotted tube 19 is disposed within the longitudinal slotted tube 12, is utilized to connect the helically slotted actuating sleeve 19 rigidly to the barrel and also to stiffen said sleeve thereby practically eliminating the "give" due to the presence of the slot. For the purpose indicated, I provide a tubular sleeve to encircle the propelling and repelling mechanism, preferably so shaped (in cross-sectional contour) as to provide a plurality of long narrow chambers for individual leads. In the form shown the sleeve 24 is corrugated, giving it a star-shaped cross section, and is of such size as to fit the propelling and repelling mechanism snugly while the points of the outer edges of the corrugations bear closely against the inner surface of the barrel 10. In the bottom of one of the grooves is a longitudinal slit 25, to expose the underlying slotted sleeve 19 when the parts are assembled, as in Fig. 5. The two are then secured rigidly together by small points or tacks of solder in the slit, as shown at 26, between successive turns of the helix. The magazine sleeve and the actuating sleeve thus become in effect one piece, and the actuating sleeve is made as rigid and strong as if it had no helical slot in it at all. In other words, operation of the pencil to advance or retract the lead cannot twist the tube 19 or cause any lengthwise movement thereof. When the magazine sleeve and the lead-actuating mechanism are assembled in the barrel, preferably with their rear ends flush, the sleeve is rigidly attached to the barrel, as by a drop of solder 27, Fig. 6. The three parts,—

barrel 10, magazine sleeve 24, and actuating tube 19,—are thus rigidly connected so that no movement of either can occur relatively to the others.

Rigidly fixed on the rear end of the tubular guide 12 is a short piece of tubing 28, Figs. 2 and 6, threaded to receive a knob 29. The latter serves to close the lead-magazine and may also form an ornamental finish for the pencil. Upon unscrewing the knob the magazine chambers are accessible for removing or inserting the extra leads, as indicated at 30, Fig. 6.

The magazine sleeve 24 is preferably made of metal, but it may be of non-metallic material, as cardboard or fiberboard, in which case it can be fastened to the slotted actuating tube 19 and the barrel 10 in any convenient and suitable manner other than soldering, for example by means of rivets or screws, not shown.

To advance the lead the barrel 10 is rotated clockwise (as viewed from the rear end of the pencil) relatively to the tip 11. This turns the magazine 24 and the helically slotted actuating tube 19 in the same direction; and since the lugs 16 and 18 cannot turn with the sleeve 19 they must move outwardly in the longitudinal slot 13, thus moving the lead-carrier 14 outwardly, as will be readily understood. To retract the lead the barrel is turned counterclockwise relatively to the tip 11, thereby moving the lead-carrier 14 backwardly. To eject the lead from the carrier the latter is advanced as far as it will go, by turning the barrel clockwise. When the lug 16 reaches the flat end of the tube or sleeve 19, further rotation of the latter (by turning the barrel) cannot advance lug 16, since the latter is then no longer engaged in the helix. Instead, it is left in the plane in which it is shown at 16^a, Fig. 3. On the other hand, the lug 18, which actuates the plunger 17, is still in the helix or screw-slot, as indicated at 18^a, Fig. 3, and hence continues to advance as the barrel is turned. The lug 18 and plunger 17 therefor move outwardly relatively to the carrier 14 and thus push the lead out of the latter. Reverse rotation of the barrel withdraws the plunger relative to the carrier until lug 16 is again in the screw slot, after which both the carrier and the plunger move back together. A fresh lead can then be inserted in the carrier.

It is to be understood that the invention is not limited to the details of construction herein described, as these can be varied widely without departing from the spirit of the invention as defined by the appended claims.

I claim:

1. A pencil of the class described, having relatively rotatable outer parts, lead-actuating mechanism, including a helically slotted

sleeve or tube, a magazine for extra leads surrounding the sleeve or tube, fastened to the sleeve or tube between the turns of the slot whereby the sleeve or tube is stiffened and strengthened, and connected to one of the said outer parts of the pencil whereby rotation of such part rotates the sleeve.

2. A pencil of the class described, comprising a barrel, lead actuating mechanism in the barrel at the axis thereof and operated by relative rotary movement of its parts, a tapered tip forming the writing end of the pencil to which a part of the mechanism is connected, the barrel and tip being 10 rotatable with respect to each other; and means surrounding the lead-actuating mechanism, serving as a magazine to hold extra leads, and as a direct connection between the barrel and a part of said mechanism where- 15 by rotation of the barrel relatively to the tip will operate said mechanism.

3. In a pencil of the class described, in combination, a central guide tube having a longitudinal slot, a lead-carrier movable 25 longitudinally in said tube and having a lug extending radially into the slot, a rotary device surrounding the guide tube and engaging the lead-carrier lug to move the lead-carrier lengthwise in the guide tube, a rotatable 30 magazine member to hold extra leads, surrounding and connected directly to the said rotary device to rotate the same, and means to rotate the magazine member.

4. In a pencil of the class described, an 35 axially aligned barrel and writing tip rotatable relatively to each other, a magazine for extra leads comprising a corrugated sleeve fitted in and secured to the barrel, lead actuating mechanism inside the sleeve and having a rotary actuating member directly connected to the corrugated sleeve, and a removable closure for the rear end of the sleeve.

5. In a pencil of the class described, an 40 axially aligned barrel and a tapered tip, forming the writing end of the pencil, rotatable relatively to each other, a guide tube co-axial with the barrel inside the same and having its forward end fixed to said tip, a

lead-carrier movable in said guide tube to advance the lead, a rotary sleeve surrounding 45 the guide tube and co-operating with the lead-carrier to actuate the same, combined with a magazine for extra leads surrounding 50 said rotary sleeve and connected directly to the sleeve and to the barrel to rotate the former, and a closure removably carried by 55 the rear end of the guide tube to close the rear end of the magazine.

6. In a magazine pencil, the combination with axially extending lead actuating mechanism, of a rotary magazine for extra leads surrounding said mechanism and directly connected thereto to actuate the same, and means for rotating the magazine to actuate 60 said mechanism and move the lead carried 65 thereby.

7. In a magazine pencil, a barrel; lead-actuating mechanism arranged axially in the barrel, and adapted to carry a lead substantially as long as the barrel; and a rotatable 70 magazine surrounding the lead-actuating mechanism inside of the barrel, extending substantially the full length of the barrel to hold leads of corresponding length and connected with said mechanism to actuate the 75 same.

8. In a magazine pencil, a barrel; a relatively short lead-feeding member at the axis of the barrel and movable longitudinally thereof; a long longitudinally slotted tube 80 and a long helically slotted tube arranged one inside of the other and around the lead-feeding member; a lug on said member extending into the slots in said tubes; a writing tip rotatable relatively to the barrel at 85 one end thereof and connected to the inner one of said tubes; and a magazine rigidly connected to the outer tube and surrounding the same, extending substantially the full length of the barrel and rigidly connected 90 therewith; whereby leads substantially as long as the barrel can be carried and used in the pencil.

In testimony whereof I affix my signature.

HARRY P. FAIRCHILD.
